UNITED STATES PATENT OFFICE.

ADAM DICKEY, OF BOSTON, MASSACHUSETTS.

ANTIFRICTION DRAWER-SLIDE.

SPECIFICATION forming part of Letters Patent No. 781,275, dated January 31, 1905.

Application filed October 1, 1904. Serial No. 228,743.

To all whom it may concern:

Be it known that I, ADAM DICKEY, of Boston, county of Suffolk, State of Massachusetts, have invented an Improvement in Antifric- 5
tion Drawer-Slides, of which the following description, in connection with the accompanying drawings, is a specification, like characters on the drawings representing like parts.

This invention relates to antifric- 10
tion slides, and has for its object to improve and simplify the construction of the same to the end that the parts composing them may be conveniently carried in stock, notwithstanding the wide variation in sizes required, and, 15
furthermore, may be assembled on short notice and a very durable drawer-slide produced.

Figure 1 shows in side elevation a drawer-slide embodying this invention. Fig. 2 is a 20
plan view of the drawer-slide. Fig. 3 is a transverse section of the drawer-slide, taken on the dotted line 3 3, Fig. 1. Fig. 4 is a side view of a portion of the frame-bar. Fig. 5 is a transverse section of the frame-bar shown 25
in Fig. 4, taken on the dotted line 6 6. Figs. 6 and 7 are enlarged side and plan views, respectively, of the journal-support.

a represents the drawer, having attached to its side a horizontal strip or bar *a'*, adapted 30
to rest upon the drawer-slide to be described.

b represents a horizontal strip or bar attached to the casing, upon which the drawer-slide rests. The drawer-slide consists of a horizontal frame-bar *c*, of any suitable length, 35
prepared in the following manner to receive a set of antifric-
tion-rolls: The frame-bar *c* has a shallow groove formed along one side of it throughout its length, as shown at *c'*, and at intervals along the grooved side of said 40
frame-bar circular recesses *c''* are formed adapted to receive the antifric-
tion-rolls.

The antifric-
tion-rolls are made as circular disks *d*, each having a central hole to receive the journal. To support the antifric- 45
tion-rolls *d*, metallic plates *e*, of suitable dimensions, are placed in the groove in the side of the frame-bar *c*, crossing the circular recesses *c''*, and said plates *e* have formed upon one 50
side of them a cylindrical lug *e'*, adapted to project into the central holes in the antifric-
tion-rolls and serve as journals upon which said rolls revolve. The metallic plates *e* are

secured in place by screws or otherwise. The plates *e* are made of a thickness substantially equal to the depth of the groove, so that when placed therein they will not project beyond the outer side or face of the frame-bar, and thereby obstruct free longitudinal movement of the drawer-slide. The antifric-
tion-rolls and the metallic plates having the journals 55
6c and the grooved frame-bars can be conveniently carried in stock at all times, and the device can be assembled by merely boring circular recesses in the grooved frame-bars at the required points and attaching the anti- 65
friction-rolls.

At the rear or inner end of the frame-bar an upright extension is provided, the extremity of which is designed to engage the casing as the drawer is slid in and out. 70

Having thus described my invention, what I claim as new, and desire to secure by Letters Patent, is—

1. In an antifric-
tion drawer-slide, a frame- 75
bar having circular recesses in one side of it, antifric-
tion-rolls contained in said recesses, and journal-supporting plates crossing said recesses, which are attached to said frame-bar, substantially as described.

2. In an antifric-
tion drawer-slide, a frame- 80
bar having circular recesses in one side of it, antifric-
tion-rolls contained in said recesses, metallic plates having journals thereon for said rolls, and means for securing said plates to the frame-bar, substantially as described. 85

3. In an antifric-
tion drawer-slide, a frame- 90
bar having a groove in one side of it extending longitudinally thereof, and having circular recesses in its grooved side at intervals, antifric-
tion-rolls placed in said recesses, and metallic plates placed in said groove, crossing said recesses, having laterally-extended lugs which project into central holes in the anti- 95
friction-rolls, and serve as journals therefor, and means for attaching said plates to the frame-bar, substantially as described.

In testimony whereof I have signed my name to this specification in the presence of two sub-
scribing witnesses.

ADAM DICKEY.
